(57) **CLAIM**

The ornamental design for a go-cart, as shown and described.

DESCRIPTION

FIG. 1 is left front perspective view showing our new design for a go-cart;

FIG. 2 is a left rear perspective view thereof;

FIG. 3 is a left side elevational view thereof;

FIG. 4 is a front elevational view thereof;

FIG. 5 is a top view thereof; and,

FIG. 6 is a left front perspective view of a second embodiment of our new design that includes a different front bumper design.

The right side of the go-cart is the mirror image of the left side.
